UNITED STATES PATENT OFFICE.

PETER FRAY, OF TAMPA, FLORIDA.

MOLDING-FLASK.

1,110,679.

Specification of Letters Patent. Patented Sept. 15, 1914.

Application filed December 16, 1913. Serial No. 806,947.

To all whom it may concern:

Be it known that I, PETER FRAY, a citizen of the United States, residing at Tampa, in the county of Hillsboro, State of Florida, have invented certain new and useful Improvements in Molding-Flasks; and I do declare the following to be a clear, full, and exact description of the same, such as will enable others skilled in the art to which it appertains to make and use the same, reference being had to the accompanying drawings, and to the characters of reference marked thereon, which form a part of this application.

15 This invention relates to improvements in molding flasks and is particularly designed as a flask for molding pump shells for rotary pumps and particularly for that type used in mines and for dredging purposes 20 where they are subjected to a large amount of heavy usage and wear.

The object of the invention is to produce a molding flask whereby the shells, while being molded or cast, may be chilled which 25 will harden them and make them better able to stand the wear and tear to which they may be subjected in practice.

A further object of the invention is to produce a simple and inexpensive device 30 and yet one which will be exceedingly effective for the purposes for which it is designed. These objects, I accomplish by means of such structure and relative arrangement of the parts as will fully appear 35 by a perusal of the following specification and claims.

On the drawings, similar characters of reference indicate the corresponding parts in the several views.

40 Figure 1 is a top plan view of the complete flask showing the casting in position therein and the molding sand removed from the upper portion of the same so as to show the location of the parts. Fig. 2 is a sectional view of the same taken on a line X—X of Fig. 1. Fig. 3 is a fragmentary view 45 of the outside of the drag and cope of the molding flask showing the means for holding a cooling conduit in position. Fig. 4 is a sectional view taken on a line Y—Y of Fig. 3.

50 Referring now more particularly to the characters of reference on the drawings, the numeral 1 designates the bottom board of the flask and the numeral 2 the drag or lower portion of the flask provided with an inwardly

projecting flange 3 on its upper inner edge. The numeral 4 designates the cope or upper portion of the flask and the numeral 5 designates the molding sand.

55 In making my improved pump shells, the same are made in two halves, one half being molded at a time and in the drawing the numeral 6 designates one of these halves as it appears after having been molded or cast in the sand 5. It is during the molding or casting period that I desire to chill the same for the purposes set forth and this I accomplish by means of the following structure and operation, namely:

70 I provide a metallic conduit 7 of substantially the shape of the interior of the casting 6, which conduit 7 projects through one side of the flask where it is provided with an inlet opening 8. Said conduit is also 75 provided with an interior outlet pipe 9 which projects centrally through the bottom of the flask, whereby, when the water is admitted through the inlet 8 it travels completely around the conduit 7 and out the 80 pipe 9. This conduit 7 is provided with a plurality of projecting arms 10 through which are screw mounted set screws 11 which impinge against the flanges 3 whereby the 85 position of the conduit 7 may be accurately determined. Said arms 10 project normally 90 through the under edge of the cope 4 and are provided with slots 12 adapted to receive swinging pins 13 on the drag 2 which are adapted to receive keys 14 in order to hold 95 the conduit 7 in fixed position and away from the casting 6 during the pouring operation.

The metal for the casting 6 is poured 95 through the openings or ingates made in the sand in the usual manner and as the same flows into the molding sand and around the conduit 7, a stream of cold water 100 is passed into the inlet 8 through said conduit 7 and out the pipe 9, which cold water 105 will form the chill for the casting as can readily be seen.

Disposed around the conduit 7 and at the lower edge of the cope 4 is the usual cake core 16.

110 As has been stated, while the metal is being poured into the sand to form the casting, the cold water is carried through the conduit 7 which quickly chills the casting and then as soon as the iron commences to get stiff, the keys 14 are removed and the bolts 13 disengaged from the arms 10 and

then the set screws 11 are operated to lift the conduit 7 away from the casting.

The flask is provided with the usual pin and key structure 18 to join the cope and drag together in the usual manner.

From the foregoing description it will readily be seen that I have produced such a device as substantially fulfills the objects of the invention as set forth herein.

10 While this specification sets forth in detail the present and preferred construction of the device, still in practice, such deviations from such detail may be resorted to as do not form a departure from the spirit 15 of the invention.

Having thus described my invention what I claim as new and useful and desire to secure by Letters Patent is:—

20 1. A device of the character described comprising the combination with a molding flask, of a conduit adapted to be disposed adjacent the member to be cast, said conduit being provided with an inlet and outlet and means for adjusting the position of said 25 conduit, within said flask, as described.

2. A device of the character described comprising the combination with a molding

flask, of a conduit adapted to be disposed therein adjacent the member to be cast, said conduit being provided with an inlet and 30 outlet, projecting arms on said conduit, and set screws projecting through said arms and impinging against a portion of said flask whereby the position of said conduit may be 35 adjusted by the movement of said set screws, as described.

3. A device of the character described comprising the combination with a molding flask, of a conduit adapted to be disposed therein adjacent the member to be cast, said 40 conduit being provided with an inlet and outlet, projecting arms on said conduit, said arms projecting through the sides of said flask, and means mounted on said flask and adapted to engage said arms to hold said 45 conduit in fixed position, and means for adjusting the position of said conduit, as described.

In testimony whereof I affix my signature in presence of two witnesses.

PETER FRAY.
